UNITED STATES PATENT OFFICE.

KENNETH M. WEST, OF PRESTON, CUBA.

SMOKING PIPE.

Application filed August 30, 1927. Serial No. 216,464.

My invention relates to a smoking pipe, and particularly to a pipe having at the bottom of the bowl a chamber for the collection of saliva.

5 The general object of my invention is to provide a pipe of the indicated character improved in various particulars, whereby the smoke passage through the stem from the bowl is made entirely independent and maintained out of communication with the collecting chamber for the saliva, as well as to provide a pipe in which the chamber for the collection of saliva is of a novel form readily cleaned.

15 Reference is to be had to the accompanying drawing forming a part of this specification, it being understood that the drawing is merely illustrative of one example of the invention.

20 Figure 1 is a view partly in section and partly in elevation of a smoking pipe embodying my invention.

Figure 2 is an enlarged vertical section of the lower portion of a pipe bowl and its appendages.

25 Figure 3 is a fragmentary plan view of the bowl and a portion of the stem.

Figure 4 is a plan view of the closure for the saliva chamber.

30 In carrying out my invention in practice in accordance with the illustrated example, a bowl 10 is provided with a stem 11 having a mouthpiece 111. At the bottom of the bowl is a passage or passages 13 extending downwardly for the escape of any saliva collecting in the bottom of the bowl. The passages 13 lead to an enlarged chamber 14 beneath which is a saliva cup 15 having a drain spout 16 leading therefrom to one end of a closure 17 in which said cup 15 and spout 16 are formed.

35 The closure 17 is rockably mounted on a horizontal pivot pin 20. The bottom of the bowl is formed with a recess or cut-out 19 in which the closure 17 is arranged. One end of the

closure 17 is subject to the pressure of a coil 45 spring 18 in said chamber 19, the spring tending to maintain the closure 17 in position with the cup 15 and spout 16 directly adjacent to the enlarged chamber 14, so as to receive the saliva from said enlarged chamber 14. 50

It is to be noted that the smoke passage 12 leading from the bowl through the stem of the mouthpiece 111 is entirely independent of the chamber 19 as well as independent of the saliva cup 15, so that there is no possibility of the saliva being drawn from cup 15 or chamber 19 through the stem to the mouthpiece 111. Pressure against the closure 17 at one end will rock the stem on the pivot, thereby giving the closure a tilted position with 60 the spout 16 remote from the adjacent surface of the bowl so that the saliva may run freely from the cup 15 and said spout when the closure 17 is tilted on its pivot 20.

65 I would state furthermore that while the illustrated example constitutes a practical embodiment of my invention, I do not limit myself strictly to the exact details herein illustrated since, manifestly, the same can be considerably varied without departure from 70 the spirit of the invention as defined in the appended claim.

I claim:

A smoking pipe including a bowl, a stem on the bowl having a mouthpiece, and a vertically rockable element on the bowl at the bottom, said element having a saliva cup formed thereon at the top, said bowl having an opening in the bottom thereof to direct saliva to said cup and having a chamber in 80 which said rockable element is arranged, the bowl and stem having a smoke passage leading to the mouthpiece, said smoke passage being entirely cut off from and independent of the saliva cup and the said chamber. 85

Signed at Antilla, Province of Oriente, Cuba, this 19th day of August, 1927.

KENNETH M. WEST.
